(57) **CLAIM**

The ornamental design for a wireless earphone, as shown and described.

DESCRIPTION

FIG. 1 is a front and top perspective view of a wireless earphone, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 2; and,

FIG. 11 is an exploded view thereof.

The broken lines in the figures illustrate portions of the wireless earphone that form no part of the claimed design. The dash dot dash lines in FIGS. 1, 2, 9 and 10 are for the purpose of illustrating the enlarged views and form no part of the claimed design. The appearance of any portion of the article between the disassembled or exploded portions of FIG. 11 form no part of the claimed design.
